(57) **CLAIM**

The ornamental design for signage, substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of the first embodiment of a signage, showing our new design;

FIG. 2 is a front elevation view thereof;

FIG. 3 is a rear elevation view thereof;

FIG. 4 is a side elevation view thereof;

FIG. 5 is the opposite side elevation view thereof;

FIG. 6 is a top plan view thereof;

FIG. 7 is a bottom plan view thereof;

FIG. 8 is a perspective view of the first embodiment of the signage shown in an environment of use;

FIG. 9 is a perspective view showing the second embodiment of a signage, showing our new design;

FIG. 10 is a front elevation view thereof;

FIG. 11 is a rear elevation view thereof;

FIG. 12 is side elevation view thereof;

FIG. 13 is the opposite side elevation view thereof;

FIG. 14 is a top plan view thereof;

FIG. 15 is a bottom plan view thereof; and,

FIG. 16 is a perspective view of second embodiment of the signage shown in environment of use.

All broken line portions of the figure drawings are included to show environment that forms no part of the claimed design.

(Continued)

The crosshatching and tonal shading shown in the figure drawings represent a contrasting appearance.

**1 Claim, 8 Drawing Sheets
(4 of 8 Drawing Sheet(s) Filed in Color)**
